United States Patent Office

Des. 188,850
Patented Sept. 20, 1960

188,850

TELEPHONE CONNECTION BOX OR SIMILAR ARTICLE

Edward B. Clark, Milford, Conn., assignor to General
Electric Company, a corporation of New York

Filed Feb. 12, 1960, Ser. No. 59,366

Term of patent 14 years

(Cl. D26—14)

FIG. 1.

FIG. 2.

FIG. 3.

Fig. 1 is a perspective view of a telephone connection box or similar article showing my design.

Fig. 2 is a back view of the connection box illustrated in Fig. 1.

Fig. 3 is a side view of the telephone connection box illustrated in Fig. 1.

I claim:

The ornamental design for a telephone connection box or similar article, substantially as shown and described.
